(57) **CLAIM**

I claim the ornamental design for a computer lamp, as shown
and described.

DESCRIPTION

FIG. 1 is a perspective view showing a computer lamp
according to the new design.

FIG. 2 is a front elevation view showing the computer lamp
depicted in FIG. 1.

FIG. 3 is a rear elevation view showing the computer lamp
depicted in FIG. 1.

FIG. 4 is a first side elevation view showing the computer
lamp depicted in FIG. 1.

FIG. 5 is a second side elevation view showing the computer
lamp depicted in FIG. 1.

FIG. 6 is a top plan view showing computer lamp depicted
in FIG. 1; and,

FIG. 7 is a bottom plan view showing the computer lamp
depicted in FIG. 1.

Features shown in broken lines in the drawings are not part
of the claim.
